Primary Examiner — Elizabeth A. Albert

(57) **CLAIM**

The ornamental design for a plant growing unit, as shown and described.

DESCRIPTION

FIG. 1 is a top perspective view of a plant growing unit showing my new design;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 a top perspective view thereof in an extended configuration; and,

FIG. 10 a bottom perspective view thereof in the extended configuration.

The broken lines showing the water tank, timer and handle in FIGS. 1-10 are included for the purpose of illustrating environmental structure and form no part of the claimed design.

1 Claim, 10 Drawing Sheets(56)
